MASK FOR DISGUISE OR THE LIKE

Richard M. Ray, Oak Park, Ill., assignor to Old Ben Publishing Company, Inc., Chicago, Ill., a corporation of Illinois

Application July 9, 1953, Serial No. 25,858

Term of patent 7 years

(Cl. D34—2)

To all whom it may concern:

Be it known that I, Richard M. Ray, a citizen of the United States, residing at Oak Park, county of Cook, and State of Illinois, have invented a new, original, and ornamental Design for a Mask for Disguise or the like, of which the following is a specification, reference being had to the accompanying drawing, forming a part thereof, in which:

Fig. 1 is a perspective view of the mask for disguise or the like, showing my new design; Fig. 2 is a top plan view; Fig. 3 is a front view in elevation; Fig. 4 is a side view in elevation; and Fig. 5 is a rear view in elevation.

I claim:

The ornamental design for a mask for disguise or the like, substantially as shown.

RICHARD M. RAY.
